UNITED STATES PATENT OFFICE.

OTTO PETERMANN, OF GROTON, NEW YORK, ASSIGNOR TO CORONA TYPEWRITER COMPANY, INCORPORATED, A CORPORATION OF NEW YORK.

DEAD-KEY ATTACHMENT FOR TYPE-WRITING MACHINES.

1,194,418.

Specification of Letters Patent. Patented Aug. 15, 1916.

Application filed November 8, 1912, Serial No. 730,248. Renewed May 19, 1916. Serial No. 98,671.

To all whom it may concern:

Be it known that I, Otto PETERMANN, a citizen of the Republic of Switzerland, and a resident of Groton, county of Tompkins, 5 and State of New York, have invented certain new and useful Improvements in Dead-Key Attachments for Type-Writing Machines, of which the following is a full, clear, and exact description.

10 The main object of the invention is to provide means by which a character may be printed without the usual letter-spacing movement of the carriage, the key used for such character printing being termed a dead key. The term "dead" is used to indicate that the key does not operate the means for moving the carriage for letter spacing.

Another object of the invention is to provide means whereby the dead key attachment will be adapted for use in a typewriting machine wherein the platen carriage has a series of vertical shifts for the purpose of bringing into operation the upper and lower case type.

25 A further object of the invention is to provide simple means whereby the dead key may be transformed into a live key, the operation of the key thereafter actuating the carriage moving means.

30 With these and other objects in view, the invention will be hereinafter more particularly described with reference to the accompanying drawings, which form a part of this specification, and will then be pointed 35 out in the claims at the end of the description.

In the drawings, Figure 1 is a longitudinal vertical sectional view of a portion of a typewriting machine showing my dead 40 key attachment applied thereto; Fig. 2 a detail plan view of the dead key attachment; Fig. 3 a vertical sectional view on the line III—III of Fig. 2.

While the invention is shown as applied 45 to a typewriting machine substantially like that disclosed in my Patent No. 1,121,040, dated December 15, 1914, it will, of course, be understood that it may be applied to typewriting machines of various kinds and 50 constructions.

The frame 10 may be of any suitable construction, and extending transversely between the sides thereof are rods or supports 11 on which the key levers are suspended.

55 The universal bar 12 extends transversely of

the machine over the key levers, said bar being held at its ends by links 13, said links being connected at 14 with the arms 15 of the bell-crank levers 16, there being, of course, two of such levers, one at each side 60 of the machine. The upper ends of the forwardly extending arms of these levers are connected by a transverse rod 17 and this rod normally works in a vertical slot 18 in the upper end of a rock arm 19, there being 65 two of such arms, one on each side of the machine. These arms are held to rock back and forth on the transverse rod 20, at the bottom of the frame, at each movement of the key levers and as each key lever, or the 70 space bar, is depressed. Extending transversely of the machine and rigidly secured to the upper end of the arms 19 is a rocker bar 21 so that said bar will rock with the arms 19 at each reciprocation of the universal bar. The platen carriage bed 22 may be suitably supported to move vertically and on this bed is carried a platen carriage 23 supporting the usual printing platen 24. As shown the carriage bed 22 is held to a support 80 24^a and said support is held to vertically movable posts or slides 24^b at each side of the machine. The slides 24^b are suitably guided and have their lower ends held to the transverse rod 20 on which the 85 arms 19 rock back and forth. An arm 24^c forming a part of a platen shift mechanism is held at one end to the rod 20 and at its other end is a rod or shaft 24^d by which the arm may be rocked and the slides 24^b, arms 90 19, support 24^a and platen carriage may be given a series of shift movements. Carried by the carriage bed is the escapement device which controls the letter spacing movement of the carriage. The dog carrier 25 is formed with the U-shaped integral portion 26 which is adapted to be engaged by the rearwardly extending arm of the escapement operating lever, as will be more fully hereinafter described. The dog carrier 25, shown in section in Fig. 1, may be of substantially the same construction as the dog carrier shown in my Patent No. 1,121,040, referred to, or it may be of any other suitable construction.

100 The parts thus far described may be of any suitable construction.

Mounted within the main frame on the machine and at one side is a bracket 27 in which is arranged a vertically reciprocable 110

2 controller bar 28. This bar is provided with a pin 29 which is adapted to engage the bracket and limit the upward movement of the bar; and connected to the bar is a 5 spring 30 which normally tends to raise said bar and hold the pin 29 in contact with the supporting bracket. The upper end of the bar is provided with three forwardly extending stops 31 between which are formed 10 slots 32. This bar 28 at its lower end is provided with a forwardly extending hook 33. Pivoted on the bracket at the lower end thereof is a releasing lever 34 to one end of which is connected a strong spring 35, said 15 spring normally throwing downwardly the inner end of the said lever. The inwardly extending arm of said lever overlies the hook formed on the lower end of the controller bar and forces the same downwardly, the 20 spring 35 being considerably stronger than the spring 30 connected to the controller bar. The inner end of the releasing lever is formed with one or more downwardly extending fingers 36 which are adapted to engage the upper edges of the character printing key levers 37, so that upon the depression of a key lever the said releasing bar will be raised, thereby releasing the controller bar and permitting it to be lifted by 25 its spring 30 until the stop pin 29 comes in contact with the bracket.

Pivoted on the rocker bar is an escapement operating lever 38, one arm of which extends rearwardly and forms the escapement operating tappet 39. The other arm of this lever extends laterally to the side of the machine, as shown clearly in Fig. 2, and normally lies in the path of one of the slots 32 in the upper end of the controller bar so 30 that in the ordinary operation of the rocker bar by the usual live keys the free end of said escapement operating lever will move rearwardly in said slot and operate the escapement mechanism. If, however, the dead 35 key 37 be struck the releasing lever will be raised, thereby permitting the controller bar to be lifted by its spring 30 until the stop pin contacts with the bracket. This will bring one of the forwardly projecting stops 40 31 directly in the path of the end of the escapement operating lever and prevent said lever swinging backwardly with the rocker bar. There are three stops 31 on the controller bar 28 to adapt the lever 38 to engage one of them when the dead key is 45 depressed during any one of the shift movements, or permit said lever to pass by said stops when the ordinary keys are depressed. It is manifest, therefore, that when the dead 50 key 37 is depressed the escapement operating lever will be first locked at its free end against free movement and the rocker bar will then swing rearwardly under the influence of the universal bar. The result will 55 be that the escapement operating lever will

swing on its pivot and throw the escapement operating tappet or arm of the escapement operating lever 38 laterally away from the dog carrier 25 so that said dog carrier will not be engaged thereby and the escapement 70 will not be operated to release the carriage for its letter spacing movement. It is clear, therefore, that upon the next operation of a character printing key the type will strike the carriage directly below or directly above 75 the previously printed character.

The escapement operating lever is held in its normal position with respect to the rocker bar by means of a spring 40 extending between said lever and the rocker bar, and said lever is provided with a lug 41 which normally engages the rocker bar. The rearwardly extending tappet arm of this lever is preferably disposed slightly to the left of the center line of the pivot of said lever so 85 that when said tappet arm engages the dog carrier the tendency will be to force the lug 41 against the rocker bar and to hold it there firmly during the operation of the escapement. 90

In order to lock the controller bar against upward movement and to thereby convert the dead key into a live key and to secure the operation of the carrier moving means for each operation of the dead key thereafter, a 95 locking arm 42 is pivoted to the bracket 27 and is adapted to be moved into a notch 43 in the controller bar when the said bar is in its normal position and one of the slots 32 therein is directly in line with the escapement operating lever 38. It is manifest that by locking the controller bar against upward movement the releasing lever may be raised without releasing the controller bar. With the parts in this condition of operation the 100 free end of the escapement operating lever will move rearwardly into one of the slots 32 at each operation of the rocker bar. By providing two or more of the depending fingers on the releasing lever two or more dead 105 keys may be employed.

Having thus described my invention, I claim as new and desire to secure by Letters Patent:—

1. The combination of an escapement element, a rocking and pivotally held lever adapted to actuate said escapement, means for shifting the escapement element and rocking lever vertically, a controlling bar having a plurality of engaging portions 115 spaced apart and adapted to be engaged by said escapement operating lever or permit said lever to be moved without engaging said bar, a spring tending normally to force the bar into an engaging position, a releasing lever, a spring of greater strength than the first-mentioned spring tending normally to hold the controlling bar in a disengaged position, and a key-operated lever adapted 120 to actuate said releasing lever. 125

2. The combination of an escapement element, a rocking and pivotally held lever adapted to actuate said escapement, a controlling bar adapted to be engaged by said escapement operating lever or permit said lever to be moved without engaging said bar, a spring tending normally to force the bar into an engaging position, a releasing lever, a spring of greater strength than the first-mentioned spring tending normally to hold the controlling bar in a disengaged position, and key-operated means adapted to actuate said releasing lever. 70
3. The combination of an escapement element, a rocking and pivotally held lever adapted to actuate said escapement, means for moving said lever and escapement element vertically, a controlling bar having a plurality of engaging portions spaced apart and adapted to be engaged by said escapement operating lever or permit the said lever to be moved without engaging said bar, and key-operated means to cause movement of the controlling bar. 75
4. The combination of an escapement element, a device adapted to actuate said escapement, a controlling bar having a plurality of engaging portions spaced apart and adapted to be engaged by said escapement operating device or permit said device to be moved without engaging said bar, a spring tending normally to force the bar into an engaging position, a releasing lever, a spring of greater strength than the first-mentioned spring tending normally to hold the controlling bar in a disengaged position, and a key-operated lever adapted to actuate said releasing lever. 80
5. The combination of an escapement element, a controlling bar, springs of relatively different strengths acting on said controlling bar, a key-operated lever adapted to permit the stronger spring to overcome the tension of the other spring to move the controlling bar, and means adapted to be actuated by the controlling bar to operate the escapement element. 85
6. The combination of an escapement element, a controlling bar, springs of relatively different strengths acting on said controlling bar, means adapted to be engaged by the controlling bar to actuate the escapement, and means for releasing the tension of one of the springs. 90
7. The combination of an escapement element, a vertically movable controlling bar, springs of relatively different strengths acting on said controlling bar, escapement actuating means adapted to be engaged by said controlling bar, and means for controlling one position of said bar. 95
8. The combination of controlling means and means adapted to be actuated by said controlling means to operate escapement mechanism or to prevent the same from be- 100
- ing operated, a releasing lever forming a part of the controlling means and having a plurality of engaging parts, and a plurality of key-levers acting upon said releasing lever to control the action of the escapement. 70
9. The combination of escapement operating mechanism, a releasing lever forming a part of the controlling means for said mechanism, and a plurality of key-levers independent of and acting directly upon said releasing lever each adapted to control the action of the escapement. 75
10. The combination of an escapement operating lever, a controlling bar adapted to be engaged by said escapement operating lever or the latter moved without being engaged by said controlling bar, a spring normally forcing the controlling bar vertically, a releasing lever, a spring of greater strength forcing the releasing lever and controlling bar against the action of the first-mentioned spring, and a key-operated lever adapted to move the releasing bar to permit the first-mentioned spring to shift the position of the controlling bar. 80
11. The combination of a pivotally spring held and rocking escapement operating lever, a vertically movable controlling bar adapted to be engaged by said escapement operating lever or the latter moved without being engaged by said controlling bar, a spring normally forcing the controlling bar vertically, a releasing lever, a spring of greater strength forcing the releasing bar and controlling bar against the action of the first-mentioned spring, and a key-operated lever adapted to move the releasing bar to permit the first-mentioned spring to shift the position of the controlling bar. 90
12. The combination of a character printing key, a rocker bar, a movable escapement operating device carried by said rocker bar, and means including a pivotally held releasing lever actuated by the character printing key in its printing movement to move the escapement operating device into an inoperative position. 105
13. The combination of a character printing key, a rocker bar, an escapement operating device carried by said rocker bar, and means including a spring held releasing lever actuated by the key in its printing movement to cause a relative movement between the rocker bar and the escapement operating device to render said escapement operating device inoperative. 110
14. The combination of a character printing key, a rocker bar, an escapement operating device carried thereby, means normally permitting the rocker bar and the escapement operating device to move together to operate the escapement mechanism, and means including a member acted on by springs of different tension adapted to be released by the character printing key in 125
- 130

- its printing movement to cause a relative movement between the rocker bar and the escapement operating device to thereby render the escapement operating device inoperative.
15. The combination of a character printing key, a rocker bar, an escapement operating lever carried thereby, a vertically movable controller bar normally permitting the escapement operating lever to move with the rocker bar, and a releasing lever operated by the said key in its printing movement to release the controller bar and thereby cause the escapement operating lever to move into an inoperative position.
16. The combination of a character printing key, a rocker bar, an escapement operating lever carried thereby, a vertically movable controller bar normally permitting the escapement operating lever to move with the rocker bar, a releasing lever in engagement with the controller bar, a spring connected to said lever and holding the controller bar in its normal position, said releasing lever being arranged to be engaged by the printing key in its printing movement to release the controller bar, a spring connected to the controller bar and adapted to move it into its locking position and thereby cause the escapement operating lever to move into an inoperative position.
17. The combination of a character printing key, an escapement operating device, controlling means operated by said character printing key in its printing movement to render the escapement operating means inoperative, and means for locking said controlling means to thereby secure the operation of the escapement operating means.
18. The combination of a character printing key, a rocker bar, an escapement operating device carried by said rocker bar, controlling means actuated by the printing key in its printing movement to render the escapement operating device inoperative, and means for locking said controlling means to render the escapement operating device operable through the movement of the printing key.
19. The combination of a character printing key, a rocker bar, an escapement operating lever carried thereby, a vertically movable controller bar normally permitting the escapement operating lever to move with the rocker bar, means operated by the said key in its printing movement to release the controller bar and thereby cause the escapement operating lever to move into an inoperative position, and means for locking the controller bar against vertical movement.
20. The combination of a character printing key, a rocker bar, an escapement operating lever carried thereby, a vertically movable controller bar normally permitting the escapement operating lever to move bodily with the rocker bar, a releasing lever in engagement with the controller bar, a spring connected to said lever and holding the controller bar in its normal position, said releasing lever being arranged to be engaged by the printing key in its printing movement to release the controller bar, a spring connected to the controller bar and adapted to move it into its locking position and thereby cause the escapement operating lever to move into an inoperative position.
21. The combination of a character printing key, a rocker bar, an escapement operating lever carried thereby, a vertically movable controller bar normally permitting the escapement operating lever to move bodily with the rocker bar, a releasing lever in engagement with the controller bar, a spring connected to said lever and holding the controller bar in its normal position, said releasing lever being arranged to be engaged by the printing key in its printing movement to release the controller bar, a spring connected to the controller bar and adapted to move it into its locking position and thereby cause the escapement operating lever to move into an inoperative position, and means to lock the controller bar against vertical movement whereby the escapement operating means will be actuated through the movement of the said printing key.

This specification signed and witnessed this 4th day of November A. D. 1912.

OTTO PETERMANN.
